CIGARETTE ARTICLE

Marvin L. Folkman, Shaker Heights, Ohio

Application December 29, 1944, Serial No. 570,350

2 Claims. (Cl. 128—185)

1

My invention consists of a novel form of cigarette intended to be used as a substitute for ordinary all-tobacco filled cigarettes so commonly in use today.

It is known that the smoking of cigarettes of the tobacco filled kind is not only a fixed habit for many thousands of persons, but the inhalation of the tobacco smoke is, to a certain extent, injurious to the nervous system of smokers because of the nicotine contained in the tobacco.

A primary object of my invention has been to produce a substitute cigarette of the class above mentioned, which may be advantageously used by persons desiring to discontinue the smoking of tobacco-filled cigarettes, either because they consider the habit of smoking such cigarettes is injurious, or because they wish to discontinue such habit while satisfying their nervous temperaments while smoking something which cannot be injurious, or which may have additional qualities that will be beneficial to the mucous membrane, or produce a sensory impression which is analogous to that of smoking the customary tobacco cigarette while not creating any injurious effect that might be derived from the tobacco type of article.

Still another object of my invention may be said to lie in producing a cigarette substitute for the tobacco cigarette, which substitute does not need to be lighted or burned, and which, when used after the manner of smoking, namely by inhaling a volatile agent in the cigarette, will be cooling and mildly stimulating in its effects.

Still another object of my invention has been to produce a cigarette for substitute use as compared with ordinary tobacco cigarettes, my substitute providing a structure which is closely imitative of the ordinary tobacco cigarette in that it is made of a flexible plastic which has the appearance of cigarette paper, or made of a flexible plastic coated externally with a paper layer that feels and looks similar to that of the common tobacco cigarette, and which will contain a volatile agent that may consist of any one of many essential oils applied to a filler within the casing or tubular body of the cigarette of my construction. Suitable provisions are made such that the body which I use is preferably formed from a flexible plastic and will be impervious externally to moisture, and also impervious internally with respect to the particular volatile agent or oil that may be applied to the filler which is located within the said impervious tubular body or casing. Furthermore, I employ provisions, as a part of my invention, whereby the filler of the

2

substitute cigarette described will be prevented from being displaced from within the tubular body preferably of flexible plastic, and which provisions include plugs inserted in the ends of said body and of a yieldable nature. These plugs or plug members which I employ are designed primarily with a view to being impervious to the oil or volatile agent with which the filler of the cigarettes is impregnated, so as to prevent the escape of such agents by flowing along the inner walls of the tubular body. The yieldability of the plug members to which I refer is also designed especially with a view to affording a mouthing resiliency for the end portions of the cigarette which may be gripped by the lips or teeth, all with a view to providing a complete simulation, not only in respect to the appearance of my substitute cigarette, as compared with ordinary tobacco cigarettes, but in relation to the manner in which the cigarette may be yieldably retained by the lips or mouth of the person who is inhaling the same as a method of smoking.

Still another advantage of my invention is that by the peculiar body construction of my cigarette, the same may be used by the smoker, so to speak, for a considerable length of time by reason of the construction of the end portion of the tubular body of my substitute cigarette, respecting particularly the provision of the resilient plug portions, as well as the inherent resiliency of the thin plastic material from which the tubular body is made.

In the practical use of cigarette substitutes of the nature of my invention, the employment of the substitute construction which I have generally described above has been found especially advantageous for use by persons who are sick, including physically or mentally injured soldiers, sailors, or members of the armed forces who are prohibited from using tobacco cigarettes on account of the effects thereof upon the nervous system, but who are beneficially assisted in the use of a cigarette substitute such as I have indicated, by reason not only of the medicinal effects that may be afforded by such use but by reason of the satisfaction given to the person because of his ability to practice, to a large extent, the nervous habit of cigarette smoking that has been fixed upon him.

I describe in the following detailed description and show in the accompanying drawings certain preferred forms of my invention, and in respect to the drawings,

Figure 1 is a side view of a cigarette of the type of my invention.

Figure 2 is a vertical longitudinal sectional view of the cigarette illustrated in Figure 1, with the sealing caps removed.

Figure 3 is a vertical longitudinal sectional view of a modified form of cigarette which may be employed for carrying out my invention, illustrating the construction of the article previous to the forcing thereinto of the end portion of the coating body, the latter designed to be received within the tubular end of said body in the final formation of the latter.

Figure 4 is a view somewhat similar to Figure 3 but showing the finished cigarette of my invention, the sealing caps not being illustrated.

Figures 5 to 10 inclusive, respectively illustrate a series of different forms of plugs such as may be inserted in the end of the tubular body of the cigarette for preventing the filler material impregnated with the volatile agent or oil employed for inhalation purposes, from being displaced from within the tubular body.

Referring now to the drawings annexed hereto, it will be observed from Figures 1 and 2 thereof that my cigarette substitute, as I may term it in relation to tobacco cigarettes, comprises the tubular body 1 which is preferably made of thin plastic material covered by paper 2 of a nature similar to that, as to appearance or color, and feel, such as employed for wrapping ordinary tobacco cigarettes. The paper 2 may include a section 2a of corked paper where the preference of the smoker may call for what are ordinarily called tipped cigarettes. The plastic material of the tubular body 1 is intended to be sufficiently thin to be flexible so that it may yield slightly as the cigarette is held in the mouth during the inhaling operation, in imitation of the ordinary smoking process.

Received in the tubular body 1 intermediate the ends thereof, and practically contained throughout the body except near the end portions, is a filler 3 made of air-pervious wool yarn, cotton rolls, granules of silica gel, or made from carbon or charcoal, all of which classes of material will be oil absorbent. It is this filler 3 which is impregnated with the essential oil or volatile agent through which the atmospheric air is sucked in the inhaling process of use of my new cigarette. As indicated before, there may be used essential oils or blends of same, and as examples of these I note the following:

	Per cent
Menthol	50
Peppermint oil	20
Eucalyptus oil	10
Spearmint oil	10
Wintergreen oil	10

Of course, the filler 3 is saturated with the volatile agent above mentioned, short however of liquid excess or flowage or obstruction of air flow through the tubular body 1 of the cigarette. An amount of about 0.5 c.c. has been found satisfactory as the proper quantity of each of the above volatile agents, for each cigarette, for example.

In the ends of the tubular body 1 of my cigarette I have the inserted plugs 4, these plugs being preferably made of rubber as illustrated in Figure 2, and providing sufficient obstruction at the ends of the body 1 whereby to prevent displacement of the filler material 3 from within said body. The plugs 4 in the construction of Figures 1 and 2, moreover, afford an additional function in that they are impervious to the volatile agent or oil

with which the filler 3 is saturated, and therefore they will prevent any of said oil that might tend to flow along the inner walls of the cigarette, from passing out of the ends of the tubular body 1.

As seen in Figure 1, when a cigarette of the construction shown in Figure 2 has been completely produced, it is contemplated that the volatile agent with which the filler 3 is saturated shall be retained in the body of the cigarette when not in use by means of sealing caps 5 located to extend over a short distance of the ends of the cigarette. The caps 5 may be made of gelatin, Cellophane, plastic material such as that used for the tubular body 1, or they may be made of aluminum anodized, and any one of the above materials or substitutes will be advantageously used for the purposes. In matter of fact, in respect to any of the constructions which I describe the caps 5 will be employed.

I now describe another preferred construction of my novel cigarette, shown particularly in Figures 3 and 4 of the drawings, in which construction I utilize the tubular plastic member 6 similar to that designated 1 in the previous construction described, and containing a filler 7 like that previously designated 3 in respect to the form illustrated in Figures 1 and 2. Likewise, inserted in the ends of the tubular body 6 are the plugs 8 made as described in reference to the plugs 4 shown clearly in Figure 2. In the construction of Figures 3 and 4, and as particularly observable in reference to Figure 3, the paper wrapping or coat 9 of the tubular body 6 which is applied tightly thereto, has the end portions thereof extending preliminarily a considerable distance beyond the ends of the body 6. Then this paper covering is turned in at the end portions thereof after the manner shown in Figure 4 to make the final form of the cigarette, said end portions having a somewhat conical cross section tapering inwardly as they are finally made. As seen in Figure 4, the end portions as folded in to the tubular body 6 of the cigarette substitute, speaking in reference to the end portion of the paper covering 9, are at the left of the corked paper section designated 10a and at the right of the plain paper section designated 10b.

It is an advantage of the cigarette of my construction that if a person prefers to mouth the corked tip ends of the cigarette he may do so, or he may use the opposite end of the cigarette in his mouth, since the process of inhaling the volatile agent in the cigarette is the same whether the cigarette is mouthed from one end or the other.

The paper wrapping or cover 9 of my construction of Figures 3 and 4 will be paraffin or wax treated so as to render the same impervious to oils or volatile agents impregnating the filler material 7. Any of such agents with which the filler 7 is saturated therefore, will not affect the end portions of the paper designated 10a and 10b as seen in Figure 4 under any conditions of use.

I prefer in the construction of Figures 3 and 4 to utilize the plugs 11 of the type previously described in reference to the plugs 4 of my first disclosed form of my cigarettes according to Figures 1 and 2, thus obtaining the same advantages of somewhat reinforcing the end portions of the cigarette when gripped by the teeth and yet affording the desired resiliency that is afforded very largely in cigarettes, cork tipped, or non-cork tipped, of the tobacco type.

Under certain conditions if desired, the plugs 11 may be dispensed with in reference to my con-

struction of Figures 3 and 4, and the impervious paper end members 10a availed of for preventing displacement of the filler 1 from within the tubular body 6 of this form of cigarette.

In Figures 5 and 10 of my drawings I illustrate different forms of plugs such as may be used in conjunction with my cigarette article above described, Figure 10 showing in end view the form which is illustrated in Figures 2 to 4 inclusive.

In Figure 5 the plug is composed of a center solid portion and radiating wing portions extending therefrom. In Figure 6 the plug is composed of a tubular body with web portions running to the internal periphery of the body from a common center. Figure 7 is similar to Figure 6 in its construction. Figure 8 shows a plug which has a solid body pre-formed with V-shaped peripheral grooves. Figure 9 illustrates a plug of a solid body provided with a multiplicity of small apertures. All of these plugs may be made of a length somewhat the same as shown for the plugs employed in the constructions in Figures 1 to 4 inclusive. They will have the same general characteristics and will be preferably made of rubber or a substitute material having corresponding characteristics, if desired.

From the foregoing it will be understood that I have provided a novel form of cigarette article useful as a substitute for the ordinary tobacco cigarette, and one which is especially advantageous to be employed by persons who desire to get rid of the habit of smoking tobacco cigarettes, to persons who are unable to longer continue such habit, and to persons who may be beneficially affected by medicinal qualities of the volatile agent with which the filler of the cigarette is saturated, when such agent is inhaled after the manner of use of an ordinary cigarette. In fact, my cigarette article may be used, so far as manipulation, feel, and to a certain extent, inhalation effects, with much the same satisfaction derived from the ordinary tobacco cigarette.

If desired, a material such as cellulose may be utilized in substitution for the plastic body 1 or 6 to which I have referred in respect to the modification of my cigarette article in the drawings.

The prime requisite of the body 1 is that it shall be externally impervious to moisture, and internally impervious to the action of the volatile agent.

- 5 It is desirable that filler 3 be arranged in the tube so that the resistance to air sucked through the tube (frequently called the draw) should be the same as with an ordinary cigarette, and I use a filler compacted to afford such function.
- 10 Having thus described my invention, what I claim as new and desire to secure by Letters Patent of the United States, is:
- 15 1. In a cigarette article, in combination, a resilient tubular body of flexible material, internally impervious to volatile agents, and externally impervious to moisture, an air pervious filler within the body, saturated with a volatile agent, and resilient plugs in and at the ends of the body, said plugs having air flow openings therethrough.
- 20 2. In a cigarette article, in combination, a resilient tubular body of flexible material, internally impervious to volatile agents, and externally impervious to moisture, an air pervious filler within the body, saturated with a volatile agent, and resilient plugs in and at the ends of the body, said plugs having air flow openings therethrough and formed to engage the inner periphery of the body to prevent flow of the
- 25 30 volatile agent to the ends of the body, and a paper covering member for the body.
